UNITED STATES PATENT OFFICE.

SOCRATIS K. KOTOLIDIS, OF WILMINGTON, DELAWARE.

DESIGN FOR A TOY.

Application filed February 23, 1922. Serial No. 846. Term of patent 3½ years.

To all whom it may concern:

Be it known that I SOCRATIS K. KOTOLIDIS, a citizen of the United States, residing at Wilmington, in the county of New Castle and State of Delaware, have invented a new, original, and ornamental Design for a Toy, of which the following is a specification, reference being had to the accompanying drawing, forming part thereof.

The figure is an elevation of the toy assembled.

I claim:—

The ornamental design for a toy as shown.

SOCRATIS K. KOTOLIDIS.
